UNITED STATES PATENT OFFICE.

JOHN H. BOGARD, OF SAN SABA, TEXAS.

ADJUSTABLE HEAD-GATE.

1,172,423.

Specification of Letters Patent. Patented Feb. 22, 1916.

Application filed April 9, 1915. Serial No. 20,225.

To all whom it may concern:

Be it known that I, JOHN H. BOGARD, a citizen of the United States, residing at San Saba, in the county of San Saba and 5 State of Texas, have invented a new and useful Adjustable Head-Gate, of which the following is a specification.

The present invention relates to improvements in head gates, one object of the invention being the provision of an adjustable gate adapted to be used in connection with irrigation ditches, the gate being so constructed as to be readily moved from place to place and to be presented across any portion of the ditch, the gate being laterally adjustable to accommodate the same to varying widths of ditches, and being provided with means for locking the sections of the gate extended.

20 A further object of the present invention is the provision of a gate of this character provided with a handle carried member which in turn constitutes a support for the laterally movable wings or sections of the gate, vertically sliding means being provided for controlling the extension or collapse of the sections or wings so that the same may be operated either through foot or hand power as desired.

25 A further object of the present invention is the provision of a gate of this character, which is simple, inexpensive and durable in construction, and thoroughly efficient and practical in use.

30 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

35 In the drawings, Figure 1 is an elevation of the present device viewed from the operating side thereof. Fig. 2 is an edge view of the device as illustrated in Fig. 1. Fig. 50 3 is a view similar to Fig. 1 but showing the opposite side of the gate. Fig. 4 is a top plan of the gate as illustrated in Fig. 1, the operating handle being shown in section. Fig. 5 is a section taken on line 5—5 of Fig. 55 1. Fig. 6 is an enlarged detail perspective

of the pawl and locking means for holding the sections extended.

Referring to the drawings, the numeral 1 designates a vertical strip or plate which constitutes the carrying member for present 60 gate, the strip being provided at one end with a pointed earth entering prong 2, and being equipped with two straps or bands 3 at the opposite end which are adapted to receive an operating handle or helve 4. Attached by means of a rivet 2' or other fastening device to the side of the entering prong 2 of the member 1 is a plate 2^a, which constitutes a guiding means for the sections 7 and 7' of the gate. Connected to the member 1 and located upon the same side thereof as the guiding member 2^a, is a headed pin 5, which is received in slots 6 and 6' fashioned in the gate sections 7 and 7', so that the gate sections will be permitted 70 straight line lateral movements to and from each other to admit of the collapse or extension of the gate, the lower edges of the sections 7 and 7' being guided in the member 2^a. 80

The outer and the lower edges of the sections 7 and 7' are strengthened by means of a reinforcement 8. Coöoperating with each section is an auxiliary gate 10, which is mounted for sliding movement in a frame 9. 85 By this means the size of the opening controlled by the auxiliary gate 10 may be regulated to permit any desired flow of water through the present head gate when the same is in place in the ditch. 90

Slidably mounted in cleats 11 and 11^a upon the carrying member 1 and disposed upon the side opposite to the guiding member 2^a is a plate 12, the same being mounted for longitudinal movement relatively to the member 1. The plate 12 is provided with a foot operating offset 13 upon its lower end and with a hand operating offset 14 at its upper end. 95

Links 17 are pivotally connected as shown 100 at 50 with the plates 7' and 7, links 18 being pivotally connected as shown at 51 with the plates 7' and 7. The links 17 and 18 are provided with longitudinal slots 52 having lateral extensions 53. A headed pin 15 enters the member 12 and is adjustable in the slots 52 of the links 17, the pin 15 being adapted to be engaged in any pair of extensions 53 of the links 17. A pin 16 is carried by the member 12 and is received 110

in the slots 52 of the links 18, the pin being adapted to be lodged in any pair of the extensions 53 of the links 18. The inner ends of the links 17 and 18 therefore are pivotally assembled with the member 12 and by moving the member 12 longitudinally, the links 17 and 18 may be employed for moving the plates 7 and 7' in opposite directions or toward each other to widen the gate in the one instance or to decrease the width thereof in the other. The pins 15 and 16 may be engaged in any of the slot extensions 53 to vary the effective length of the links, the links being provided with handles 54 which facilitate a shifting of the positions of the links with respect to the pins 15 and 16.

In order to provide a means for locking the member 12 in its lowest position when the sections 7 and 7' are extended, the prong 2 having been pushed into the earth at the bottom of the ditch, a longitudinal slot 19 is formed in the member 12, one edge of the slot being provided with ratchet teeth 20 disposed in coöperable relation with a pawl 21, said pawl 21 being pivoted at 22 to the member 1 and being provided with a weighted end 23 which normally holds the locking end 21 against the teeth 20. The pawl 21 may be released manually so that the member 12 may be moved toward the handle 4 to collapse the section 7 and 7'.

From the foregoing description, it is evident that a gate constructed according to and embodying the present invention, is portable, and may be readily carried from place to place, and be manipulated similarly to a shovel, in that the handle 4 may be so operated to place the entering point 2 at the center of the ditch, with the wings or sections 7 and 7' transversely of the ditch, it merely being necessary to push the operating member 12 either by foot or hand downwardly to extend the sections 7 and 7' so that the outer edges thereof and the bottom portions will be placed in engagement with the outer edges or walls and the bottom of the ditch.

By reason of the fact that the pawl and ratchet device locks the member 12 in its downward position, the sections 7 and 7' are thus held extended with the marginal edges thereof entering the earth at the bottom and side walls of the ditch while the entering point 2 anchors the device at its lowermost point.

What is claimed is:

1. In a device of the class described, a carrying member; gate sections mounted to slide transversely of the carrying member; an actuating element mounted to slide longitudinally of the carrying member; means for holding the actuating element in adjusted positions on the carrying member; links pivoted at their outer ends to the gate

sections and provided at their inner ends with longitudinal slots having transverse extensions; and projections carried by the actuating element, the projections being adapted to move in the slots and to be lodged in any of the extensions for adjustment.

2. In a head gate, a ground entering carrying member; laterally movable gate sections operating upon opposite sides of the carrying member; interengaging elements connecting the sections with the carrying member for right line lateral movement; an actuating element mounted to slide longitudinally of the carrying member; means for operatively connecting the actuating element and the sections to produce a right line lateral movement of the sections when the actuating element is depressed; an automatically acting locking device forming an operative connection between the carrying member and the actuating element; and a projection on the actuating element and adapted to be engaged by an operator to secure simultaneously a depression of the carrying member and a lateral expansion of the gate sections, the projection being independent of the locking device.

3. An adjustable head gate, including a longitudinal strip constituting a carrying member, a pair of transversely movable sections mounted upon the carrying member, an actuating plate connected to the carrying member for longitudinal reciprocatory movement, coöperating collapsing extension means attached to the actuating plate and to the sections, whereby the sections are collapsed and extended when the actuating plate is reciprocated, a foot actuating means carried upon the lower end of the actuating plate, a hand actuating means carried upon the upper end thereof, and coöperating means carried by the carrying member and the actuating plate for locking the plate against movement in one direction.

4. An adjustable head gate, including a longitudinal strip constituting a carrying member, a pair of transversely movable sections mounted upon the carrying member, an actuating plate connected to the carrying member for longitudinal reciprocatory movement, coöperating collapsing extension means attached to the actuating plate and to the sections, whereby the sections are collapsed and extended when the actuating plate is reciprocated, a foot actuating means carried upon the lower end of the actuating plate, a hand actuating means carried upon the upper end thereof, said actuating member being provided with a plurality of ratchet teeth, and a pivoted pawl mounted upon the carrying member and disposed in coöperative relation to the teeth to lock the actuating member and the sections against collapsing.

5. An adjustable head gate, comprising a plate provided with an earth entering point upon one end and a handle receiving member upon the opposite end, a handle 5 mounted in the handle receiving end, two sections attached to the plate for extension and collapse, an actuating plate mounted upon the first plate for movement longitudinally of the first plate, said actuating plate 10 being provided with an offset foot engaging portion at one end and an offset hand engaging portion at the opposite end, two pairs of links pivotally connected to the actuating plate and to the sections whereby 15 the reciprocation of the actuating plate causes the extension and collapse of the sections, said actuating plate being provided with a plurality of longitudinally disposed ratchet teeth, and a pawl pivotally connected 20 to the carrying plate with its engaging end in cooperation with the teeth of the actuating plate and so arranged as to permit the free movement of the actuating plate in one direction.
- 25 6. An adjustable head gate, comprising a plate provided with an earth entering point upon one end and a handle receiving member upon the opposite end, a handle mounted in the handle receiving end, two sections

attached to the plate for extension and collapse, an actuating plate mounted upon the first plate for movement longitudinally of the first plate, said actuating plate being provided with an offset foot engaging portion at one end and an offset hand engaging portion at the opposite end, two pairs of links pivotally connected to the actuating plate and to the sections whereby the reciprocation of the actuating plate causes the extension and collapse of the sections, said 30 actuating plate being provided with a plurality of longitudinally disposed ratchet teeth, and a pawl pivotally connected to the carrying plate with its engaging end in cooperation with the teeth of the actuating 35 plate and so arranged as to permit the free movement of the actuating plate in one direction, said pawl being so arranged as to engage the teeth and lock the sections 40 against accidental collapse.

50 In testimony that I claim the foregoing as my own, I have hereto affixed my signature in the presence of two witnesses.

JOHN H. BOGARD.
